UNITED STATES PATENT OFFICE.

HENRI ALEXANDRE PERNOT, OF PARIS, FRANCE.

CLOSURE FOR CONTAINERS.

Application filed June 3, 1924, Serial No. 717,465, and in France June 9, 1923.

This invention relates to closures for containers of conical shape.

The object of this invention is to provide a closure for such containers at a low cost, and one which is easily secured in position.

According to this invention the closure consists of a metallic cap with a flat or dished top and with a flange which is grooved around its circumference, forming a rib on the inside.

10 Means are provided for tearing off portions of the flange for facilitating the removal of the cap.

Preferably the diameter of the cap is equal to or slightly greater than the external diameter of the containers at its rim, but the inside diameter of the rib is smaller than that of the container at its rim.

When the cap is placed on the top of the container it is prevented from passing into 20 position, owing to the rib formed on the inside, the inner surface of which bears against the rim of the container. If, however, the can be pressed down, the rib which has a certain amount of elasticity, momentarily gives 25 way and passes over the rim immediately clamping itself tightly on to the neck of the container, where it acts as a retaining ring preventing the cap from being easily removed.

30 The groove may be substantially semi-circular or may comprise two substantially conical portions so arranged as to be V-shaped in cross section. Moreover the upper conical portion has preferably an angle at the apex 35 larger than that of the lower portion.

Of course the groove formed by the two conical portions may be smooth or interrupted.

40 The wall of the flange of the cap may be cylindrical like the upper part and as is usual; it may be remarked that when the cap is placed in position the lower part of the flange closes in on to the container.

45 The accompanying drawing shows the application of this invention to a conical shaped glass jar, such as a jam jar or mustard pot.

Figure 1 is a view in elevation of the container and closure. Figures 2 and 3 are detail sectional views of the container and its 50 cap showing the cap removed and in closing position respectively. Figure 4 is an elevation of a modification. Figures 5 and 6 are views in elevation and in section respectively of a further modification. Figure 7 is an elevation of a modification of a cap after positioning. Figure 7^a is a diametral section to a

larger scale of the edge of the cap. Figure 8 shows a view of such cap taken at right angles to that of Figure 1. Figure 9 shows the cap positioned on its container. Figure 10 is 60 a sectional elevation of a modification.

In Figures 1 to 3, the glass jar A is closed by means of a metallic cap with a dished top, 1, having a circumferential groove 2, forming an internal rib of smaller diameter than that 65 of the rim a of the container.

As shown in Figure 3, after the cap has been forced into position on to the neck of the container, the rib 2, owing to its elasticity, grips 70 tightly onto the neck of the container, preventing any upward movement of the cap.

The cap has formed on its flange one or more grooved or ribbed tabs or tongues 3, which when torn off lessens the grip of the rib on the neck of the container, allowing the 75 cap to be easily removed by hand.

Referring to Figure 4, instead of the tab or tongue 3, a slit 4 is provided into which the end of some suitable tool may be inserted for facilitating the removal of the cap.

The cap, instead of having a dished top, 80 may be flat and may rest upon a round plate of metal, cardboard or other material, which closes the container. In this case the flange of the cap 1 need not be continuous or provided with the tabs or tongues, instead its two ends may overlap one another and be secured together by means of a rivet 6 or other suitable arrangement as shown in Fig. 5. To remove the cap, it is sufficient to pull on the external end 7 of the flange, so as to disengage 85 the rivet 6.

It should be understood that any other means may be provided in place of those described for permitting the removal of the cap. 90

Moreover, the rib on the flange of the cap may be of any other suitable shape, as, for instance, several conveniently spaced projections may be provided around its periphery.

Referring to Figures 7 to 9 the rib 2 is 100 conical, 2^a being the upper portion and 2^b the lower portion, the angle at the apex of 2^b being smaller than the angle at the apex of 2^a and the conical section 2^a being correspondingly shorter than the section 2^b. The 105 lower part 2^c of the flange is cylindrical. The cap is provided with an opening tab 3.

In Figure 9 there is shown the effect of compressing the part 2^c of the cap against the body of the container A. This step exerts a leverage, owing to the difference of 110 inclination of the parts 2^a and 2^b to further

compress the rib 2 against the container and also causes the part 2^a to assume conical form and to lie closely adjacent to the conical wall of the container.

5. In Figure 10 the rib 2 in place of being continuous is interrupted by cylindrical circular portion 2^a or the rib may comprise projecting portions of any desired shape.

In place of a tab 3 the cap may be provided 10 with other opening means.

What I claim is:—

1. In combination with a container having a frusto-conical portion adjacent the opening 15 therein, a closure for said opening, said closure including a top and a securing flange, said flange including an inwardly projecting rib and a substantially cylindrical portion beneath said rib, said rib being capable of being forced over the conical portion of said 20 container and of clamping itself thereto, said rib being formed of two angularly arranged portions the upper of which is shorter than

the lower portion and arranged at a greater angle with respect to the vertical than the lower section, the difference in angularity of 2 the two portions causing the substantially cylindrical portion to assume a conical form upon application of pressure to the rib incident to the application of the closure to a container.

2. A closure including a top member and a circumferential securing flange, said securing flange including an inwardly projecting securing rib and a substantially cylindrical portion beneath said rib, the upper portion 35 of said rib being arranged at a greater angle with relation to the vertical than the lower portion of said rib and means whereby a portion of said flange may be torn away to facilitate removal of the cap. 40

In testimony whereof I have affixed my signature.

HENRI ALEXANDRE PERNOT.
